Primary Examiner — Jennifer Rivard*Assistant Examiner* — Alison M Ofstun(74) *Attorney, Agent, or Firm* — Heslin Rothenberg Farley & Mesiti P.C.(57) **CLAIM**

The ornamental design for a junction box for catenary light, as shown and described.

DESCRIPTION

FIG. 1 is a perspective view of a junction box for catenary light, showing our new design;

FIG. 2 is a front elevation view thereof, the back view being a mirror image thereto;

FIG. 3 is a right side view thereof, the left side view being a mirror image thereto;

FIG. 4 is top plan view thereof; and,

FIG. 5 is a bottom plan view thereof.

The shorter broken lines represent portions of the article that form no part of the claimed design. The longer broken lines represent environmental structure that forms no part of the claimed design.
